[57] CLAIM

The ornamental design for a knight chess piece, as
shown.

DESCRIPTION

FIG. 1 is a front view of a knight chess piece showing
my new design;

FIG. 2 is a top view of the knight chess piece of FIG. 1;
and

FIG. 3 is a side view of the knight chess piece of FIG.
1.

The side views of the Pawn, Rook, Queen and King
chessmen are identical to their front views illustrated in
FIG. 1.
